UNITED STATES PATENT OFFICE.

WILLIAM H. HONISS, OF HARTFORD, CONNECTICUT, ASSIGNOR TO HARTFORD-FAIR-MONT COMPANY, OF CANAJOHARIE, NEW YORK, A CORPORATION OF NEW YORK.

GLASS-DELIVERING APPARATUS.

Application filed November 10, 1921. Serial No. 514,179.

To all whom it may concern:

Be it known that I, WILLIAM H. HONISS, a citizen of the United States, residing at Hartford, in the county of Hartford and State of Connecticut, have invented new and useful Improvements in Glass-Delivering Apparatus, of which the following is a specification.

This invention relates to apparatus for delivering charges of molten glass from a furnace outlet or other source of supply to a plurality of molds or to different sets or series of molds. One object is to provide for the delivery of mold charges to the molds while the latter are moving, thereby enabling the mold carrying tables to be constantly rotated instead of stopping to receive each successive charge. A further object is to provide, in combination with suitable charge forming and feeding apparatus and a plurality of molds or sets of molds, improved means for selectively transferring and delivering the charges from the feeding apparatus to the molds or to any preferred type of glass shaping machines.

An important feature of the present invention is the provision of an inclined trough or transfer member extending from beneath a furnace outlet or charge forming device and having a plurality of outlets through which the charges may be selectively delivered to molds at different receiving stations, by manipulation or movement of the transfer member.

The trough may be varied in shape or design to a considerable extent, so long as by manipulation or movement of the same, it is capable of delivering to molds at different receiving stations, and for this purpose it is preferably provided with a plurality of outlets through which the charges may be selectively delivered in any predetermined order. In the present instance the trough is provided with two branching delivery channels, which are adapted to deliver to two different series or sets of molds, carried by tables which are preferably mounted for continuous rotation, although the tables may be intermittently rotated if desired. The trough is mounted for oscillation upon an inclined axis extending longitudinally thereof, so that the trough outlets may swing in a path located in a plane

extending at an angle to the horizontal, whereby the lowered end is brought into 55 delivering relation with the traveling mold. The swinging movement of the delivering end of the trough on its inclined axis causes it to move in a curved path which approximately conforms to the curved path or orbit 60 of travel of the mold, as viewed from above, so as to allow for variations which are liable to occur in the time of delivery, the position of the delivering end of the trough being suitable for directing the glass in its 65 proper trajectory to the mold, even when the delivery is early or late.

One embodiment of the invention is illustrated in the accompanying drawings, in which:

Fig. 1 is a plan showing the trough adapted for delivery to two different mold carrying tables.

Fig. 2 is a front elevation of the apparatus shown in Fig. 1.

Fig. 3 is a side elevation of the machine with the feeding apparatus in section.

Fig. 4 is a detail plan of the trough or transfer device.

Fig. 5 is a longitudinal section through 80 the trough on line 5-5 of Fig. 4.

Fig. 6 is an enlarged transverse section on line 6-6 of Fig. 4.

Fig. 7 is a side elevation, partly in section, of a modified form of the invention, 85 and

Fig. 8 is an enlarged transverse section on line 8-8 of Fig. 7.

In the present embodiment of the invention, 10 represents the forehearth of a furnace or molten glass container having a discharge outlet 11 and an implement 12 for controlling the discharge of the gobs or mold charges 13, which may be severed by any suitable means, such as the shear blades 90 14, actuated by any well known shear mechanism. The mold charges 13, when severed, drop by gravity into the upper end of the inclined trough or transfer member 15, which is wide enough at its receiving point 100 to insure the proper entrance of the charges therein. At its lower end the trough is provided with a plurality of outlets, from which the charges are discharged at an angle to the body of the trough, the outlets being preferably in the form of branching channels 105

16 and 17, although they are not necessarily limited to this form of construction. The branches 16 and 17 merge smoothly into the body of the trough so that the charges will be directed into whichever channel is in lowered position at the time the charge reaches the point where the trough divides. The body and branches of the trough are substantially of uniform size and contour, and of such shape as will best maintain the charges in their original form as delivered from the charge producing apparatus. As shown in Figs. 1 to 3 inclusive, the branch 16 is in lowered position for delivering to one of the molds of the right-hand series 18 while the opposite branch 17, for delivering to the molds of the left-hand series 19, is in raised position, thereby directing the charge into the lowered channel.

20 The tables 20 and 21, carrying the two sets or series of molds 18 and 19 respectively, are supported by suitable frames or standards 22 and are preferably geared together and driven by a gear 23 on a suitably driven shaft 24. However, the tables may be otherwise mounted and driven in any preferred manner, either continuously or intermittently. The trough may be oscillated in various ways best suited to the design or construction of the machines with which the device is employed, whereby the charges may be selectively delivered to different sets of molds, so that a greater number of charges may be successively delivered to one set of molds than to another, if preferred. In the present embodiment the trough is provided with trunnions 25 and 26 journaled in the upper and lower brackets 27 and 28 (Fig. 3).

40 The trough is preferably made substantially semicircular in cross section and the axis 29 thereof, about which it is oscillated, passes approximately through the longitudinal center of the trough and through said bearings, although if desired the axis may be at an angle to the body of the trough or may be inclined to any extent required for obtaining the desired curved movement of the delivering ends when delivering to molds which move in circular or curved paths. For delivering to molds which move in an approximately straight line, the axis may be horizontal. The axis preferably passes approximately through the center of that part of the trough which receives the charge, as it falls from the furnace outlet, so as to minimize the lateral movement of the sides of the trough at this point, whereby to insure the delivery of the charge to the trough when the latter is rocked to its extreme delivering positions. Any suitable means for rocking the trough may be employed. In the present instance, the trough is provided with a beveled gear sector 30 driven by a rack, or by a gear 31 fixed on a shaft 32

supported upon brackets 33 and 34, the latter of which is extended upwardly to support the bracket 28 carrying the lower end of the trough.

Upon the shaft 32 is fixed an arm 35 having a roll 36 at its outer end, engaging a cam 37 on the bottom of the mold carrying table 20. Also fixed on the shaft 32 is an arm 38, and a spring 39 connects the arm with the frame 22 or with any convenient support to retain the roll 36 in contact with the cam 37. Rotation of the table and the cam 37 effects oscillation of the shaft 32, which through the rack 31, oscillates the trough to cause the delivery of the charges to the different sets of molds. The cam for oscillating the trough may be mounted separately from the table, or be made in separate parts, or adjustably mounted on either table so that it may be adjusted forwardly or backwardly to vary the time of the swinging movement of the trough relative to the movement of the rotating table. The cam may be provided with relatively long and short dwell periods to effect the delivery of a greater number of charges to one set of molds than to the other, if desired. The entire mechanism for moving the trough may, if desired, be separate from the tables and driven in proper timed relation with respect thereto.

In the modification shown in Figs. 7 and 8, the general construction is substantially the same as in the other views, the difference being that the trough consists of two sections, the upper section 40 being supported in fixed position upon a bracket 41, while the lower portion 42 is provided with a trunnion 43 journaled in a relatively long bearing 44, preferably carried by an extension on the bracket 34. The movable section 42 is oscillated in the same way and by the same means as in the preferred form of the apparatus, and is adapted to deliver to the different sets of molds precisely in the same manner as in the preferred form. The movable section 42 is adapted to at all times be in position to receive the descending charge 13 (Fig. 8) from the fixed section 40 of the trough, since the axis about which it is oscillated passes substantially through the centers of both sections. In this form it is not necessary to enlarge the upper end of the trough section 40, since it is permanently fixed in receiving position and may, therefore, be made relatively narrow to correspond more nearly to the size of the charge.

The term "selectively," as used in the specification and claims, means that the number of charges being delivered to the different sets of molds and the order of succession of such delivery may be varied to suit different conditions. In ordinary practice the trough would be oscillated to de-

liver charges alternately to the two mold tables. However, its operation may be changed by suitably modifying the cams, as stated above, so that it will deliver any desired number of charges in succession to one table and thereafter deliver any desired number in succession to the other table, or delivery may be made in any other order found advisable. This feature will be of advantage in cases where it is desired to complete an order on the same machine at the same time for glassware of different shapes, sizes or weights and for different quantities of each.

15 The illustrated embodiment of the invention may be modified and changed to a considerable extent without departing from the scope of the invention as expressed in the claims.

20 What is claimed as new is:—

1. Apparatus for conveying charges of molten glass, comprising a trough provided with a plurality of outlets, and automatic means for moving the trough and the outlets 25 to cause the charges to be selectively discharged through said outlets.

2. Apparatus for delivering mold charges, comprising a transfer device mounted for oscillation and having a charge receiving portion and a plurality of discharge portions, each of which communicates with said receiving portion, and automatic means for oscillating the transfer device and the discharge portions to cause the charges to be 35 selectively delivered through said discharge portions.

3. Apparatus for delivering mold charges, comprising a transfer device mounted to swing upon an axis and having a charge receiving portion, and outlets on opposite sides of said axis communicating with said receiving portion, and means for rocking said device about said axis to cause the charges to be selectively guided to said outlets.

4. Apparatus for conveying charges of molten glass, comprising an inclined trough mounted on an axis extending longitudinally thereof, the trough being adapted to alternately discharge upon the opposite sides of its axis when moved thereon, and automatic means for moving the trough upon said axis to determine the point of discharge of successive charges.

5. Apparatus for conveying charges of molten glass, comprising an inclined trough having its lower end provided with a plurality of outlets continuous with the trough and adapted to discharge at an angle to the body of the trough, and means for moving the trough to cause the charges to be selectively discharged through said outlets.

6. Apparatus for conveying charges of molten glass, comprising an inclined trough 65 mounted on an axis extending longitudi-

nally thereof, said trough having laterally extending channels at its lower end, and means for rocking the trough to cause the charges to be discharged from said channels alternately.

7. Apparatus for conveying charges of molten glass, comprising a movable guide for receiving and directing the charges to different predetermined points, including outlet portions extending laterally from the guide and in fixed relation thereto and means for moving the guide to cause the charges to be delivered through said outlet portions to said points in a predetermined order.

8. Apparatus for transferring charges of molten glass from a source of supply to a plurality of receptacles located at different receiving points, comprising a transfer member permanently in receiving position and having a plurality of outlets, and means for moving said member to bring said outlets into position to discharge into said receptacles at the different receiving points.

9. Apparatus for conveying charges of molten glass, comprising a guide for receiving and directing the charges to different predetermined points, said guide including laterally extending discharge channels, and means for effecting the raising and lowering of the channels to cause them to selectively deliver the charges to said points.

10. Apparatus for transferring charges of molten glass periodically delivered from a source of supply to a plurality of receptacles located at different receiving stations, comprising a movable transfer member provided with a guideway having a plurality of outlet channels leading therefrom corresponding to the number of receiving stations, and means for moving said transfer member in timed relation to the delivery of the charges to effect delivery of the charges selectively through said channels into the receptacles at the respective stations.

11. Apparatus for conveying charges of molten glass from a source of supply to a plurality of molds, comprising a transfer device permanently in receiving position and having a laterally extending discharge portion, and means for oscillating said device to cause the end of said discharge portion to move in a path located in a plane at an angle to the horizontal while moving into and out of delivering position.

12. Apparatus for transferring charges of molten glass from a source of supply to a plurality of molds, comprising a trough having a receiving portion and a separate discharge portion provided with a plurality of outlets, said portions having adjacently mounted ends, said discharge portion being mounted upon an axis coinciding substantially with the centers of said ends, and means for moving said discharge portion

- upon said axis to cause the charges to be selectively discharged through said outlets to said molds.
13. The combination with means for feeding charges of molten glass and a plurality of sets of molds, of a movable transfer member for receiving the charges from the feeding means having a single receiving portion and a plurality of outlets communicating therewith, and means for actuating the transfer member and different sets of molds to selectively position the outlets in delivering alignment with the molds of the different sets.
14. The combination with means for feeding molten glass and a plurality of movable molds, of a movable transfer member for receiving the charges from the feeding means having a single receiving portion and a plurality of outlets communicating therewith, and means for actuating the transfer member and molds to selectively position the outlets in delivering alignment with the different molds while moving.
15. The combination with means for feeding charges of molten glass and a plurality of sets of continuously moving molds, of a movable transfer member for receiving the charges from the feeding means having a single receiving portion and a plurality of outlets communicating therewith, and means for actuating the transfer member and different sets of molds to selectively position the outlets in delivering alignment with the molds of the different sets while moving.
16. The combination with means for feeding charges of molten glass and a plurality of movable molds adapted to be charged at different receiving stations, of a movable transfer device having a receiving portion and a plurality of outlets communicating therewith corresponding to the number of receiving stations, means for moving said transfer device to selectively position said outlets in delivering alignment to the molds at the respective stations, and means for moving the molds to and from the stations.
17. The combination with means for feeding charges of molten glass and a plurality of sets of molds movable to different receiving stations, of a trough having a single receiving portion and a plurality of outlets leading therefrom, and means for actuating the trough and different sets of molds to selectively position the outlets in delivering alignment with the molds at the respective stations.
18. The combination with a glass feeding apparatus for supplying mold charges and a plurality of mold supports having molds thereon, of a transfer device having a receiving portion and a plurality of outlet portions communicating therewith, means for effecting movement of said mold supports relative to each other, and means controlled by one of said supports for moving said transfer device to cause the charges to be selectively delivered through said outlet portions to the molds of the different supports.
19. Apparatus for handling molten glass, comprising a feeder for periodically delivering mold charges, a plurality of molds successively placed in different charge receiving positions, an inclined trough having its upper end in receiving relation to the feeder and its lower end provided with opposite laterally inclined outlets, and means for rocking the trough about its approximate longitudinal axis in timed relation to the presentation of the molds whereby an outlet is lowered into delivery position for co-operating with each mold when it is in charge receiving position.
20. Apparatus for handling molten glass, comprising a feeder, a Y-shaped delivery trough mounted to receive the glass on the stem of the Y and having its fork inclined downwardly, a pivotal mounting for the trough having its axis approximately coincident with the receiving portion of the trough, molds, means for positioning the molds alternately on each side of said axis, and means for rocking the trough on its axis to lower the forks alternately in time with the positioning of the molds.

Signed at Hartford, Connecticut, this 7th day of November, 1921.

WILLIAM H. HONISS.
